(57) **CLAIM**

The ornamental design for a cap lamp, as shown and described.

DESCRIPTION

FIG. 1 is a perspective view of the cap lamp;

FIG. 2 is a front elevational view of the cap lamp;

FIG. 3 is a rear elevational view of the cap lamp;

FIG. 4 is a left side elevational view of the cap lamp, the opposite side of which is a mirror image;

FIG. 5 is a top plan view of the cap lamp; and,

FIG. 6 is a bottom plan view of the cap lamp.

The broken lines shown are included for the purpose of illustrating the unclaimed portions of the article and form no part of the claimed design.

1 Claim, 6 Drawing Sheets

FIG. 1

FIG. 2

FIG. 3

FIG. 4

FIG. 5

FIG. 6
